Bernays Johnson
BY
J. H. Gobert

ATTORNEY

UNITED STATES PATENT OFFICE.

BERNAYS JOHNSON, OF NEWARK, NEW JERSEY, ASSIGNOR TO WESTINGHOUSE LAMP COMPANY, A CORPORATION OF PENNSYLVANIA.

ELECTRIC LAMP FOR PROJECTION APPARATUS.

Application filed September 15, 1921. Serial No. 500,918.

To all whom it may concern:

Be it known that I, BERNAYS JOHNSON, a citizen of the United States, and a resident of Newark, in the county of Essex and State of New Jersey, have invented a new and useful Improvement in Electric Lamps for Projection Apparatus, of which the following is a specification.

This invention relates to incandescent electric lamps and more particularly to electric lamps for use in projection apparatus.

In projection apparatus used in the exhibition of motion pictures, stereopticons, slides, etc., a light source of high intensity is required. This light source must be highly concentrated in order to be effectively utilized in obtaining a given screen illumination. This is due to the fact that the opening in the aperture plate of the projection machine is small and all light cast upon the screen must be focused to pass therethrough.

In some forms of incandescent lamps now used as light sources, the filament arrangement is of the mono-plane or bi-plane type, and a reflector is required to effect a solid source of light which is focused upon the aperture plate. These lamps are customarily designed to consume 600 or 900 watts and are either 30 volt 20 ampere or 30 volt 30 ampere. This voltage being lower than commercial voltages, necessitates a transformer and auxiliary apparatus to permit using the lamp.

If the length of the filament in the mono-plane or bi-plane lamp is increased to permit its direct use upon a 110 volt circuit, several sections of the filament extend beyond the opening in the aperture plate, i. e., the width of the filament is greater than the width of the aperture plate opening. Consequently, the light derived from the outer sections is lost for projection purposes.

It is an object of my invention to provide such mounting or arrangement of the filament of an incandescent lamp that a given voltage may be obtained and no appreciable portion of the light produced be lost on account of the filament extending over a given area.

Another object of the invention is the provision of an incandescent lamp having its filament arranged in such manner that, when viewed in the direction of a projecting axis, the effect is that of a solid beam of

light restricted to a given area of distribution.

A further object of the invention is the production of lamps having their filaments so arranged that the necessity of reflectors, in obtaining a uniform screen illumination, is materially reduced and in some instances eliminated.

Other objects of the invention will be apparent from a reading of the following description.

In the drawings which form a part of this specification,

Fig. 1 is a view, in elevation, of a lamp partially broken away to show my preferred arrangement of filament;

Fig. 2 is a sectional view taken on line II—II of Fig. 1; and,

Fig. 3 is a diagrammatic illustration of the arrangement of the filament sections, showing the effective illuminating portions thereof.

Referring to the drawings and particularly to Fig. 1, a lamp 1 is shown as comprising a filament 2 mounted within a gas-filled envelope 3. The filament 2 comprises a plurality of coiled sections supported in a V formation by wires 4 and 5 and connected to leading-in conductors 6. The length of the filament is determined by the normal voltage at which the lamp is to be operated. For example, a lamp of given wattage and voltage has a longer filament than a lamp of the same wattage and lower voltage. My invention provides for so mounting the several sections that each of them, irrespective of the length of the filament, is effective for projection purposes. These sections may be mounted within the lamp envelope in any desired manner, with the one restriction that the opening of the V formation does not substantially exceed the width of the aperture in the aperture plate of the projection apparatus, for the obvious reason that any sections mounted outside the limits of the aperture plate opening are of no assistance in illuminating the screen, as the light rays therefrom cannot be focused within this opening.

I have found that, by arranging the sections in a V-shape, all of the sections are readily positioned within the allowable overall width, and that, as the number of sections increase, the depth of the V will increase. Figs. 2 and 3 illustrate the maxi-

2
mum width between which the filament sections may be effectively mounted. End sections 7 and 8 are shown spaced apart a distance within the maximum width in order 5 to have their emitted light rays pass through the standard size opening in an aperture plate. In the spacing of the several sections comprising the filament, consideration should be given to prevent the overheating, 10 or undue overlapping of adjacent sections, i. e., from the standpoint of overheating, they should not be placed too closely together, or, from the standpoint of overlapping immediately behind one another when 15 viewed in the direction of the projecting axis of the lamp.

In arranging the filament section in V shape, I prefer to have substantially the same number in each of the sides or legs 20 comprising the V, and the central or apex section from which the others diverge so designed as to substantially coincide with the optical axis of the projection apparatus. For convenience of designation, the sections 25 in each leg of the V may be referred to as being a series of sections positioned in a common plane, although it is to be understood that my invention is not to be considered as being limited to having each filament section located directly in a particular 30 plane. When the number of sections is large, the actual amount of surface of each section emitting effective light rays is smaller than when the number of sections is 35 reduced. For illustration, reference may be had to Fig. 3 wherein it is assumed that line 10 is a representation of the opening in an aperture plate through which the light rays must pass. It will be noted that about two- 40 thirds of each section is capable of casting effective illuminating light rays through the plate opening. The effective lighting surface may be varied, but I have found that, in the present type of motion picture projection apparatus, this arrangement has 45 proved satisfactory.

Lamps constructed in accordance with my 50 invention, wherein the sections are of substantially equal length and arranged in a V shape, to allow the central or apex section to be positioned on the optical axis, cast substantially solid beams of light through the aperture plate to the screen. Such construction provides a more uniform distribution of light on a given screen area than has heretofore been obtained, and it is found 55 that, by employing this filament arrangement, reflectors, which are usually employed in projection and reproduction apparatus, 60 may be eliminated or may be used only in cases where it is desired to smooth out the

screen by casting the images between sections which became warped or displaced. The use of lamps contemplated by my invention give a light-ray distribution approximating more nearly the ideal uniform light distribution than has heretofore been possible with any other type of lamp. 65

When desired, the lamp may be positioned so that the V arrangement will be side-wise 70 to the optical axis of the apparatus and so that the sections in the series more remote from the nearest condensing lens will effectively admit their light rays between the sections of the series which is nearer the 75 lens.

The lamp herein described as a selective embodiment of my invention is capable of creating a more uniform screen illumination and of having substantially all of its sections 80 utilized for projection purposes. Also my lamp admits of the sections being uniformly heated, thus preventing a particular section from being overheated. Modifications and other changes in the arrangement hereinbefore described, may be made by those skilled in the art, but such modifications and changes are considered as being within the scope of this invention, as defined by the 85 following claims. 90

What is claimed is:

1. An electric lamp having a filament comprising a plurality of coiled sections of substantially equal length, said sections being disposed in two planes which meet to 95 form a V, the sections in each side of the V being parallel to the meeting line and disposed behind and overlapping one another, and a coiled section at the meeting line also arranged parallel to the other sections 100 and overlapping the sections immediately adjacent thereto, the said sections being spaced from each other a sufficient distance to avoid arcing therebetween. 105

2. An electric lamp having a filament comprising a plurality of coiled sections, said sections being disposed in two planes which meet to form a V, the sections in each side of the V being parallel to the meeting line and disposed behind and overlapping one another, and a coil section at the meeting line also arranged parallel to the other sections 110 and overlapping the sections immediately adjacent thereto, the said sections being spaced from each other a sufficient distance to avoid arcing therebetween and being substantially of equal lengths. 115

In testimony whereof, I have hereunto subscribed my name this 14th day of September, 1921.

BERNAYS JOHNSON.
